UNITED STATES PATENT OFFICE

MAX TRUNZ, OF BROOKLYN, NEW YORK

BACON SLICER

Application filed July 7, 1928. Serial No. 290,944.

This invention relates to slicing machines, and particularly to an improved bacon slicing machine which may be readily adjusted to slice bacon on a bias or in the usual transverse manner.

Another object is to provide a slicing machine wherein bacon or other meat may be supported and fed either horizontally or upwardly on an incline to a cutting knife which 10 functions the same regardless of the angle of the bacon.

A still further object of the invention is to provide a slicing machine which may be adjusted during the operation of the machine 15 so as to cut at different angles according to the thickness of the bacon.

A still further object of the invention is to provide a bacon slicing machine wherein a specially constructed pivotal support is provided for one end of the bacon table so that the bacon may be swung at different angles 20 without the end of the table moving away from a certain vertical line.

In the accompanying drawings,—

25 Figure 1 is a front view of a bacon slicing machine disclosing an embodiment of the invention;

Figure 2 is an edge view of the machine shown in Figure 1;

30 Figure 3 is a sectional view through Figure 2 on the line 3—3;

Figure 4 is a perspective view showing part of a pivotal support for the bacon supporting table;

35 Figure 5 is a sectional view showing part of a bacon supporting table with one end of the pivotal support therefor;

Figure 6 is a sectional view through Figure 5 approximately on the line 6—6;

40 Figure 7 is a sectional view through Figure 1 on the line 7—7;

Figure 8 is a sectional view through Figure 7 on the line 8—8;

Figure 9 is an enlarged fragmentary sectional view through Figure 8 on the line 9—9.

Referring to the accompanying drawings by numerals, 1 indicates a frame of any desired kind which is provided with any desired number of bracing members 2 so as to 45 hold the frame in proper place. At or near

the top of the frame 1 is a shaft 3 supported in suitable journal boxes and carrying at one end a knife 4 used for cutting the meat, as hereinafter fully described. At the end of shaft 3 opposite knife 4 is arranged a sprocket 55 wheel 5 carrying a chain 6 which may be of the silent type or any desired type. This chain passes over a sprocket wheel 7 connected to the shaft of the electric motor 8 which is supported on a suitable bracket or support 9 connected in any desired manner with the frame 1. A sprocket wheel 10 is connected with shaft 3 and accommodates the sprocket chain 11 which passes over a sprocket wheel 12, whereby whenever motor 8 is functioning 60 knife 4 will be functioning and sprocket wheel 12 will be rotating. As shown in Figure 7, the sprocket wheel 12 is rigidly secured to a shaft 13 which carries a gear wheel 14 continually meshing with an idler 15 which 65 in turn meshes with a pinion 16 rigidly secured to shaft 17. This shaft is provided with a universal coupling 18, whereby the tubular shaft 19 may be rotated and yet 70 swung upwardly and downwardly. A shaft 75 20 is splined to the hollow shaft 19 and is connected to the shaft 21 by a universal coupling 22. The shaft 21 is carried by suitable bracket 23, said bracket being rigidly secured to a bacon table 24, which table is swung upwardly and downwardly, as hereinafter fully 75 described. A gear wheel 25 is rigidly secured to shaft 21 and is continually in mesh with the pinion 26 which is rigidly secured to the screw 27 supporting suitable journal 80 members carried by the bacon table 24. The screw 23 is adapted to be rotated by the pinion 26 but not to move longitudinally. The function of the screw 27 is to cause the traveling member 28 to move upwardly or toward 85 the pivotal point of the table 24 to feed the bacon 29 toward the knife 4. After a piece of bacon has been fed to the knife 4 and has been cut except for a small piece at the end, certain parts of the traveling member 28 are 90 operated, whereby this traveling member is released from operative engagement with the threads of the screw 27, thus permitting this member to be moved manually back to its 95 starting point or to substantially the position 100

shown in Figures 1, 7 and 8. This is done manually and when done a new piece of meat is mounted on the table 24 ready to be forced toward knife 4. This operation may take 5 place while the machine is functioning or while the machine is not operating. The traveling member 28 and associated parts are substantially the same as shown in my co-pending application Serial No. 221,311 although some slight changes have been made 10 in certain details. As indicated more particularly in Figure 9, the traveling member 28 is provided with a sleeve 30 loosely fitting over the screw 27, said sleeve having a depending bracket 31 for receiving one end of 15 spring 32, which spring is connected at the opposite end to the extension 33 of the lever 34 pivotally mounted on pin 35. Pin 35 is journaled in suitable ears 36 extending from 20 the sleeve 30. Lever 34 is provided with a handle or grip 37, whereby it may be manually raised or lowered and when raised is held in an upper position by the spring 32. Lever 34 is provided with an elongated slot 25 38 which accommodates the pin 39 extending through the block 40 which is threaded at the lower end with threads of a size to interlock or coact with the threads of screw 27. When the parts are in the position shown 30 in Figure 9, the threads of block 40 are engaging or meshing with the threads of screw 27 and if this screw is rotating the sleeve 30 and associated parts will be propelled. In order to hold the lever 34 so that the threads 35 of block 40 will mesh with the threads of screw 27, a hook 41 extends over the upper edge of lever 34. This hook is pivotally mounted by reason of pin 42 and extends through a comparatively large aperture 43 40 in the depending arm 44. The end 45 of hook 41 is positioned so as to strike the abutment 46 when the traveling member 28 has moved to its nearest point adjacent knife 4. As soon as the hook 41 has been swung so as to become 45 disengaged from the lever 34 spring 32 will begin to function and will immediately raise block 40 out of engagement with the screw 27. If nothing is done with the traveling member 28 there will be no more feeding action, but if the machine is to be used further 50 traveling member 28 is pulled downwardly to the position shown in Figure 1 or later to the position shown in Figure 8, as the case may be, and then a new piece of bacon mounted 55 on the bacon support or table 24. When this has been done the pointed ends 47 of the swinging members 48 are forced into the end of the bacon. The members 48 are pivotally mounted on the shaft 49 which is 60 carried by the arm 44 and are preferably spaced by suitable sleeves 50. After the pointed members 47 have been properly set, lever 34 is swung downwardly and hook 41 is moved to snap thereover, whereupon the 65 traveling member 28 will begin to function for forcing the bacon toward knife 4. As long as the motor 8 is functioning knife 4 will be rotating and power will be transmitted to shaft 19 and associated parts, so that the screw member 27 will be continually rotating, whereby the traveling member 28 will function as long as block 40 is engaged with the screw 27. By reason of the universal couplings 18 and 22 power will be transmitted to the screw 27, regardless of the angle 70 thereof. This screw is mounted on the bacon support or table 24 and the support could be used in a horizontal plane, as shown in Figure 8, at an angle as shown in Figure 1 or at any intermediate point, as preferred. The 75 angle of the table 24 and the thickness of the bacon determine the width of the slice. In packing sliced bacon it is desirable to have all the slices of the same width, and consequently means have been provided for 80 quickly swinging the table 24 upwardly or downwardly at any time to take care of different thicknesses of bacon and still provide slices of the same width. As shown particularly in Figure 8, a bracket 51 is secured to 85 the bottom of the bacon table 24 and to this bracket is pivotally secured the racks 52, said racks continually meshing with a pinion 53. A guide 54 guides the racks 52 and holds the same in mesh with pinion 53. Pinion 53 is 90 rigidly secured to shaft 54' which is supported by suitable brackets 55 carried by the frame 1, said shaft at one end carrying a worm wheel 56 which continually meshes with the worm 57. The shaft 58 extending 95 from worm 57 carries a hand wheel 58' which, when rotated, causes the worm wheel and associated parts to function for raising or lowering the racks 52 and the table 24. These 100 parts may be caused to function while the other parts are functioning. In mounting the table 24 so as to swing as above outlined, a special pivotal support or mounting is provided which is shown particularly in Figures 1, 2, 4, 5 and 6. This structure is especially provided in order that the point 59 (Figure 5) will remain in the same place. As the knife 4 passes very near this point it is necessary to maintain this point in the same relative place as the table moves upwardly and downwardly, in order that the knife will not strike the table. In order to accomplish this result a disk 60 is provided and formed with a web 61 secured by bolts 62 or by other suitable means to the frame 110 1, as shown in Figure 2. It will be understood that there are two disks 60 arranged so as to face each other, as shown in Figure 2, and the description of one will apply to both. The disk 60 is provided also with an arc-shaped groove 63 designed to receive the arc-shaped web 64 of the plate 65. Plate 65 is provided with an outstanding web 66, bolted, welded or otherwise rigidly secured to the 115 table 24. The end portion of the table 24 is 120 65

secured to the respective plates 65, so that as the table is moved upwardly and downwardly the point 59 will remain in the same place. As shown in Figures 5 and 8, the parts are so proportioned as to permit the device to be used in a horizontal position, or in an inclined position. Regardless of the angle of the table 24, the point 59 of the table will remain in the same place, and consequently as the meat is forced past this point it is cut by knife 4 in the proper manner.

What I claim is:—

1. A bacon slicer, including a rotatable knife, a bacon table, means for pivotally mounting the table so that it may be swung from a substantially horizontal position to a 45° angle, means including a traveling member for forcing the bacon along said table toward said knife, and power means connected with said knife and with the means for forcing the bacon along the table, whereby the movement of the bacon will be in proportion to the speed of the knife.

2. A bacon slicing machine, including a frame, a shaft carried by the frame, power means for rotating the shaft, a knife secured to said shaft at one end and adapted to be rotated thereby, a hood substantially covering said knife, a bacon platform, a pivotal supporting member for pivotally supporting one end of said platform, so that said end will be in a fixed position in respect to the knife at all times, manually actuated means for swinging said table in a vertical plane, and power driven means for moving a piece of bacon upwardly over said table to said knife.

3. A bacon slicer, including a cutting knife, a bacon table, a pivotally mounted structure for supporting one end of the table, said pivotally mounted structure including a pair of plates, each having an arc-shaped groove and a second pair of plates formed with an arc-shaped web fitting into said groove, and a rack structure connected at one end with the bacon table, and manually actuated means for moving said rack structure for swinging said table in a vertical plane.

4. A bacon slicer, including a knife, means for rotating the knife to produce a cutting operation, a bacon table, means for feeding bacon along the platform towards the knife, and a pivotal supporting structure for the table, said pivotal supporting platform including a pair of plates secured to said bacon table, each of said plates having an arc-shaped groove structure on the arc of a circle with the center coincident with the end of the top surface of said table, and a pair of fixed supporting plates formed with arc-shaped grooves for receiving said arc-shaped flanges, whereby as said table is swung the end of the upper surface will always remain in the same place.

5. A bacon slicing machine formed with a rotatable cutter, power means for rotating

said cutter, and means for feeding bacon to the cutter at right angles or at a less angle, said means including a table, a manually actuated structure for swinging the table to various angles, and a pivotal support connected with one end of the table for holding the end of the table nearest the knife in substantially the same position relative to the knife at all times, said pivotal support including a pair of plates secured to said table, each of said plates having an arc-shaped groove with the center of the groove coincident with the end of the top surface of said table.

6. In a meat slicer, a cutting knife, a meat supporting table, a power actuated traveling member for moving the meat over said table, and a pair of pivotal supporting members connected with said table for supporting one end of the table, said supporting members being arranged on opposite edges of the table and including in their construction a pair of plates, each of said plates having an arc-shaped groove with the center thereof coincident with the end of the top surface of the table.

Signed at Brooklyn in the county of Kings and State of New York this 2nd day of July A. D. 1928.
